LAMP SHADE

Joel W. Kaufmann, San Francisco, Calif., assignor to Damron-Kaufmann, Inc., San Francisco, Calif., a corporation of California

Filed Sept. 28, 1960, Ser. No. 62,290

Term of patent 14 years

(Cl. D48—16)

FIG. 2

FIG. 1

FIG. 1 is a top plan view of my lamp shade; and
FIG. 2 is a front elevational view of my lamp shade.
The sides of the lamp shade not shown are substantially the same in appearance as the sides shown.

I claim:

The ornamental design for a lamp shade, as shown and described.
